(57) **CLAIM**

The ornamental design for a compressible article advancer, as shown and described.

DESCRIPTION

FIG. 1 is a top perspective view of a compressible article advancer in accordance with our new design and shown in an uncompressed configuration;

FIG. 2 is a bottom perspective view thereof;

FIG. 3 is a front elevation view thereof;

FIG. 4 is an opposite side elevation view thereof;

FIG. 5 is a top plan view thereof;

FIG. 6 is a bottom plan view thereof;

FIG. 7 is a side elevation view thereof;

FIG. 8 is another side elevation view thereof;

FIG. 9 is a side elevation view thereof as it would appear in a compressed configuration when positioned below items in a box; and,

FIG. 10 is a side elevation view thereof as it would appear in a partially compressed configuration when positioned below items in a box as the items are being removed from the box.

The broken lines shown in the figures represent environment and form no part of the claimed design.

1 Claim, 8 Drawing Sheets
